UNITED STATES PATENT OFFICE.

ABRAHAM M. RABINOF, OF NEW YORK, N. Y., ASSIGNOR TO ELBE FILE & BINDER CO., INC., OF NEW YORK, N. Y.

CARD INDEX FOR TELEPHONE RECEIVERS.

Application filed November 20, 1924. Serial No. 751,003.

To all whom it may concern:

Be it known that I, ABRAHAM M. RABINOF, a citizen of the United States, residing at New York, in the county of New York and State of New York, have invented certain new and useful Improvements in Card Indexes for Telephone Receivers, of which the following is a specification.

This invention relates to telephone index devices of the class in which alphabetically marked cards, serving for telephone addresses, are arranged between covers and suspended from the mouthpiece of a telephone receiver.

As usually constructed, the back of the card index device is formed with a circular opening large enough to permit the free passage thereof onto the mouthpiece of the telephone receiver. When the index is thus suspended from the mouthpiece, it has the tendency to slip off the latter, when the receiver is tilted forwardly, while in use. To prevent this, a device has been introduced, which consists of a clutch arm fixed to the back cover of the index and extending downwardly from above around the mouthpiece. But such device has been found impracticable for several reasons, among others, that the metal clutch is constantly in contact with the mouthpiece, which is undesirable, and also since the index can freely slide on the mouthpiece, the frictional contact of the clutch with the latter produces objectionable scratching noises.

The object of this invention is to provide a construction, whereby the above mentioned drawbacks will be avoided.

With this and other objects in view, my invention consists in the construction, combination and arrangement of parts, as will be hereinafter fully described and defined in the appended claims.

In the accompanying drawing in which similar reference characters denote corresponding parts, Fig. 1 is a front elevation of the index device; Fig. 2 a longitudinal section on line 2—2 of Fig. 1; Fig. 3 a rear elevation of said device, the lower part being broken off; Fig. 4 a front elevation of a modified construction and Fig. 5 a longitudinal section on line 5—5 of Fig. 4.

a denotes the back of a card index formed with a circular opening *b*, whereby it is adapted to be slipped over the mouthpiece

c of a telephone receiver. The means for preventing the card index from slipping off the mouthpiece, according to my invention, consists of a resilient member 10 applied to the back of the card index to extend across and somewhat obstruct the lower part of said opening, so that, while it will permit the passage of the mouthpiece through said opening by forcing it through the obstructed portion of the latter, the index cannot accidentally slip off the mouthpiece. This resilient member may be in form of a simple spring coil and be attached by rivets or the like on opposite sides of the opening. But instead of riveting it to the index, I prefer to use the following construction: Arranged on the front face of the back *a* of the index, is a substantially U-shaped wire 11, whose longitudinal portion is formed centrally with a loop 11' for the engagement of a rivet or the like 12, whereby it may be fixed to the back *a*. The vertically extending end portions 11² of said wire are curved substantially as shown to form loops on which perforated cards *d*, constituting the index proper, are adapted to be strung in the usual manner. The rear parts of said loops are passed through perforations *a'* of the back *a* and are bent upwardly, as at 11³. The free ends of said upwardly bent parts 11³, which terminate at points slightly above the lowest point of the periphery of the opening *b* and at opposite sides of the latter are bent to form hooks 11⁴ to which the resilient member or spring 10 can be easily attached.

The means for holding the cards and the spring 10 can thus be made in one piece, and the construction, therefore, is greatly simplified. When the index is suspended from the mouthpiece of the telephone, the spring will extend across the bottom part of the mouthpiece and while it will not be in contact with it, will form a sufficient obstruction to prevent the index from slipping off the mouthpiece.

The obstructing element can be easily attached to the hooks 11⁴ of the wire 11 and replaced whenever lost or broken without the use of tools.

Instead of using a separate spring 10, the free ends of the wire may be bent inwardly relative to the opening *b* and curved substantially as at 13 in Fig. 4, so as to nor-

mally obstruct the opening *b*. When slipping the back *a* of the index over the mouthpiece, the latter will spread the curved parts 13 apart, which subsequently will be drawn back into obstructing position by their own spring force.

What I claim is:—

1. In a telephone card index having a back with an opening to fit over the mouthpiece of a telephone receiver, a resilient obstructing element near the lower edge of said opening to prevent the index from slipping off the mouthpiece, said element being adapted when said index is on said mouthpiece to be out of contact with the latter.
2. In a telephone card index having a back with an opening to fit over the mouthpiece of a telephone receiver, a member fixed to the back of said index formed with forwardly bulging loops to hold the index cards and the free ends of which are passed through the back cover of said index, and resilient means on said member serving to obstruct the lower part of said opening to prevent the index from slipping off said mouthpiece.
3. In a telephone card index having a back cover with an opening to fit over the

mouthpiece of a telephone receiver, an attachment consisting of a member fixed to the front face of said cover and formed with forwardly bulging loops for the suspension of the index cards, the free ends of said loops being passed through said cover and extended to points somewhat above the bottom edge of said opening, and a spring coil attached to said free ends to extend across said opening and obstruct the same, so as to prevent the slipping off of said index from said mouthpiece.

4. In a telephone card index having a back cover with an opening to fit over the mouthpiece of a telephone receiver, an attachment consisting of a member of resilient material fixed to the front face of said cover and formed with forwardly bulging loops for the suspension of the index cards, the free ends of said loops being passed through said cover and extended to obstruct said opening and prevent the index from slipping off said mouthpiece.

In testimony whereof I affix my signature in presence of two witnesses.

ABRAHAM M. RABINOF.
